CLAIM

The ornamental design for a plunge cut saw and guide system, as is shown and described.

DESCRIPTION

FIG. 1 is an elevation view of a top side of a plunge cut saw and guide system.

FIG. 2 is an elevation view of a bottom side of a plunge cut saw and guide system.

FIG. 3 is an elevation view of a left side of a plunge cut saw and guide system.

FIG. 4 is an elevation view of right side of a plunge cut saw and guide system.

FIG. 5 is an elevation view of a front side of a plunge cut saw and guide system.

FIG. 6 is an elevation view of a back side of a plunge cut saw and guide system.

FIG. 7 is a perspective view of a rear-right, top side of a plunge cut saw and guide system.

FIG. 8 is a perspective view of a rear-left, top side of a plunge cut saw and guide system.

FIG. 9 is a perspective view of a front-right, top side of a plunge cut saw and guide system.

FIG. 10 is a perspective view of a front-left, top side of a plunge cut saw and guide system.

FIG. 11 is a perspective view of a rear-right, bottom side of a plunge cut saw and guide system.

FIG. 12 is a perspective view of a rear-left, bottom side of a plunge cut saw and guide system.

FIG. 13 is a perspective view of a front-right, bottom side of a plunge cut saw and guide system; and,

FIG. 14 is a perspective view of a front-left, bottom side of a plunge cut saw and guide system.
